BUILDING STRIP

Anthony Salvo, Tiverton, Albert Cayer, Smithfield, R.I., and Justine Serejczyk, Fall River, Mass., assignors to Dura-Last Shingle Corp., Fall River, Mass., a corporation of Massachusetts

Filed Nov. 7, 1966, Ser. No. 4,574

Term of patent 14 years

(Cl. D13—1)

FIG. 1 is a perspective view of a building strip showing our new design;

FIG. 2 is an enlarged end elevational view thereof looking at the right end of the strip shown in FIG. 1;

FIG. 3 is an enlarged section taken on line 3—3 of FIG. 1;

FIG. 4 is a rear elevational view thereof;

FIG. 5 is a bottom view thereof; and

FIG. 6 is a top plan view thereof.

The characteristics of my design reside in a member that has an increasing inclination from top to bottom, a bottom edge that is inclined downwardly and rearwardly, an upper edge that is parallel to the bottom edge but that is reduced in dimension with respect thereto, and an upper extension joined to the upper edge and that is substantially vertical; the aforesaid characteristics being associated in combination with a simulated wood surface that is formed as an integral part of the member.

The strip is shown broken in FIGS. 1, 4, 5 and 6 to illustrate indeterminate length.

We claim:

The ornamental design for a building strip, substantially as shown and described.
